(57) **CLAIM**

The ornamental design for an insulated boot for handling electrical conductors, as shown.

DESCRIPTION

FIG. 1 is an isometric side view of our insulated boot for handling electrical conductors;

FIG. 2 is a front elevational view thereof;

FIG. 3 is a top plan view thereof;

FIG. 4 is a bottom view thereof;

FIG. 5 is a rear elevational view thereof;

FIG. 6 is a right side elevational view thereof; and,

FIG. 7 is a left side elevational view thereof.
